BROOCH CARRYING REMOVABLE LETTERS OR LIKE FIGURES.

Application filed January 23, 1928, Serial No. 248,727, and in France December 10, 1927.

This present invention relates to a brooch carrying internal letters (or other figures) characterized by the fact that the letters are removable, and in this manner a given type 5 of brooch may be employed whatever may be the initials of the wearer, since the proper letters can be instantaneously inserted into the brooch.

The said device is characterized by the fact 10 that upon the back of the decorative part which surrounds the set of letters, we dispose a frame which is hollowed in such manner that the letters placed upon the back of said frame will appear at the front, means 15 being provided for obtaining the proper position of the letters with reference to the said frame.

Our device is chiefly characterized by a 20 novel construction of said securing means so that the decorative frame of the brooch may be made in any desirable form. Consequently the brooch may be as decorative and ornamental as heretofore with the added advantage that any letters or designs occurring 25 therein are removable and interchangeable.

The appended drawings show by way of example an embodiment of the invention constructed according to the aforesaid principles.

30 Fig. 1 is a back view of the brooch in the open position, the separate removable letters to be inserted therein being shown below. Fig. 2 is a corresponding view, with the letters placed freely in position. Fig. 3 is a 35 back view of the closed brooch, and Fig. 4 is the corresponding front view.

1 represents the decorative part of the brooch which surrounds the initial letters or like figures employed; 2 is the pin for fastening the brooch to the garment; this pin is hinged at 3 and when the device is closed, its 40 point engages in a catch 4 provided with suitable fastening means.

According to the invention, the back part 45 of the brooch has soldered thereto a frame 5 which herein has a rectangular shape, and is provided in its edges and to its inner face with regularly spaced notches 6 which are cut in the body of said frame; at the lower 50 part of the figure are shown the removable letters which are provided with studs 7 disposed symmetrically with reference to the axis of each letter, and whose relative positions enable them to engage the notches of the 55 frame 5 in such manner that any letter may

have any position in the frame. Fig. 2 shows by way of example the three separate letters of Fig. 1 freely inserted into the frame. Herein the element holding the letters in place consists of a backing frame 8 hinged at 60 9 to one of the short sides of the frame 5. The letters are mounted in place as shown in Fig. 2, the backing frame is folded down as shown at 8' in Fig. 3, so that the studs 7 of the removable letters will be held in their 65 notches 6 between the frame 5 on one side and the backing element 8 on the other. The latter is held in place in a removable manner by any suitable means; herein we provide for the purpose a small pin 10 mounted on the 70 back part of the frame 5 on the side opposite the hinge 9 and coacting with a hole 11 in the backing element 8. When the latter is brought down upon the letters to hold them in place, the pin 10 enters the hole 11; the 75 backing element can then be fastened by slightly bending the end of the pin extending above the said frame, and the letters are thus held in position.

Obviously the general arrangement and ornamentation have no particular importance as concerns the invention, and these points may be as desired.

Claims:

1. A brooch comprising a frame which is 85 mounted at the back of the surrounding decorative part of the brooch, notches at the back of said frame, signs formed to freely fit into the frame being visible through the same, said signs being provided with extensions 90 disposed to engage said notches, a backing framewise element hinged at said frame and disposed to be closed upon the back of the signs to fasten the same, a hole being bored into said backing element in another side than 95 the hinged side, a pin being fastened to the frame and disposed to engage the hole in the closed position of the backing element, and said pin being made of a ductile metal to enable it to be slightly folded over the backing 100 element for locking the same in its closed position.

2. A brooch having an apertured decorative piece, a frame shaped to correspond with the form of said decorative piece and mounted on the back thereof, notches placed about the inner edge of said frame, signs formed to fit removably into said frame and being visible through said apertured decorative face, a plurality of extensions disposed upon said signs 110

- and adapted to engage said notches in said frame, a backing element hinged on said frame and disposed to abut in closed position the back of said signs to secure the same.
- 5 3. A brooch having an apertured decorative piece, a frame shaped to correspond with the form of said decorative piece and mounted on the back thereof, notches placed about the inner edge of said frame, signs formed to fit removably into said frame and being visible through said apertured decorative

face, a plurality of extensions disposed upon said signs and adapted to engage said notches in said frame, a backing element hinged on said frame and disposed to abut in closed position the back of said signs to secure the same, and means to lock said backing element in said closed position. 15

In testimony whereof, we have signed our names to this specification.

HENRI DUFAU.
VICTOR LEGARD.
